DES
N° 1136.

Dec. 11 1866

Henry Webbard, of New York, N.Y.
Letters Patent No. 1136. Dated Aug. 23, 1866.

The schedule referred to in these Letters Patent and making part of the same.

To all whom it may concern:

Be it known that I, Henry Webbard, of the City, County, and State of New York, have invented a new and original design for ornamenting the handles of Spoons, forks, and other articles of Table Cutlery, whether from Silver or other metal, and I do hereby declare the following to be a full description of the same, reference being had to the accompanying drawings, in which the same letters of reference whenever they occur, refer to like parts.

Figure 1. is a representation of the reverse side of the Spoon, and
" 2. is a representation of the obverse side.

Letter a, represents the shield, at the head of it, and extending down upon its face, are two, shell like ornaments b, & c. each composed of six radii, branching from a convex shaped back d, which joins the two shell like ornaments together.

Between the two shell like ornaments, and upon which b rests, are two raised scrolls e, e, the ends of which f, f, gradually taper off, down the margin or edges of the shield, to the middle of the stem g, down which they

entwine till their junction with the bowl *h*, when they turn back around a drop-like raised device *b, b*, and up along the outer edge of the stem, to form a duplicate series of raised threads *i, i*, which terminate in scrolls *j, j*, at the base of the shield, —

Between the ends of the threads, at their junction with the bowl of the Spoon is an arrow headed shaped device, *k*, to complete the design for ornamenting the obverse side of the handle of the Spoon.

At the head of the shield piece on the reverse side of the handle of the Spoon, is a shield on, similar to *b*, on the obverse side, and radiating from a center piece *m*, between two scrolls *p, p*, the ends of which *q, q*, form double threads, down the sides of the shield (as on the obverse side of the Spoon) till they enter the stem, where they unite in one thread as a middle line of threads, and terminate at the heel *r* of the Spoon, in scrolls *s, s*, formed, by their union, with another row of threads *t, t*, running up the edge of the stem and terminating in scrolls *u, u*, at the base of the shield.

Between the scrolls *s, s*, are two shell-like ornaments *v, v*. These ornaments are bound together by a band *w*, and cover the heel of the spoon, to complete the design for ornamenting the reverse side of the Spoon.

Having now described my invention, I will proceed to set forth what I claim and desire to secure by letters patent of the United States.

What I claim is the use of the ornamental devices on the obverse and reverse sides of the spoon, as herein before described for the purpose of ornamenting the handles of spoons, forks, and other articles of table cutlery, whether made from silver or other metals.
